UNITED STATES PATENT OFFICE.

ARTHUR G. HUNTER, OF SHERMAN, TEXAS.

WRENCH.

1.120.386.

Specification of Letters Patent.

Patented Dec. 8, 1914.

Application filed February 7, 1914. Serial No. 817,321.

To all whom it may concern:

Be it known that I, ARTHUR G. HUNTER, a citizen of the United States, residing at Sherman, in the county of Grayson and 5 State of Texas, have invented certain new and useful Improvements in Wrenches, of which the following is a specification.

This invention pertains to wrenches of that class adapted for use in turning nuts, 10 and relates particularly to mechanism whereby the sliding jaw thereof may be approximately quickly adjusted and securely locked upon the shank, and subsequently moved into close and accurate position with 15 respect to a nut for gripping the same.

Another object of the invention is the provision of a simple attachment which, when mounted upon the shank of said wrench adapts it for use in turning pipes 20 and rods; whereby the gripping power may be applied with the maximum efficiency and the minimum risk of crushing, superficially abrading, or otherwise injuring the article grasped.

25 This invention is designed particularly to improve the type of wrench heretofore invented by me and embodied in a patent dated July 25th, 1911, No. 999,167. In its use I have found that successful operation 30 depends to a very great extent on the secure locking, adjustment and release of the sliding jaw. In my patent above named is shown a locking mechanism pivotally secured to a movable yoke, which is objectionable.

35 The principal aim therefore of the present invention is to overcome these inherent objections and to this end the invention comprises a locking device and movable yoke 40 formed of one piece. In addition to this improvement it also embodies a simple and efficient pipe gripping attachment.

By the special construction of parts hereinafter described and claimed, as well as by 45 the general combination, arrangement and coöperation of the elements entering into the mechanism as a whole, is devised a wrench which will operate with equal efficiency on either nuts or pipes of various 50 sizes.

In the accompanying drawings, Figure 1 is a longitudinal front edge view of a wrench constructed according to my invention. Fig. 2 is a side view of the same. Fig. 3 is a rear

edge view. Figs. 4 and 5 are views of the pipe 55 gripping attachment. Figs. 6 and 7 are views of the carriage. Figs. 8 and 9 are views of the movable yoke removed from the carriage.

Referring now to the drawings, it will be 60 seen that my improved wrench comprises, essentially, a primary fixed jaw 1, a shank 2, and a secondary sliding jaw 3. The jaw 1 is formed integral with the forward terminal of the shank, while the secondary jaw 65 3 is mounted for sliding movement longitudinally of the shank, adapting it in practice to coöperate with the jaw 1 for operating upon a nut or the like. In the front edge of the movable jaw 3 is provided a slot 4, intersected by alining apertures 5 in which is mounted an adjusting screw 6 having threaded engagement with a knurled disk 7 thereon that is confined within the slot in the jaw. 70

Upon the rear edge face of the shank 2, and extending longitudinally of the latter for about half of its length are formed transversely disposed ratchet teeth 8, the forward faces of which are adapted in practice for 80 engagement by coincident teeth 9, formed upon an inner end face of a movable yoke 10, that is carried by a rectangular shaped carriage 11, which is slidably mounted upon the shank 2, and extending forwardly therefrom is an extension 11^a, in which the adjusting screw 6 is secured. The movable yoke 10 is formed with a projecting finger lug 10^a, between which, and the forward end 85

of the carriage is mounted a coiled spring 90 12, the latter serving to normally sustain the teeth 9 of the movable yoke 10 in engagement with the teeth 8 in the shank, the carriage is perforated at 11^c, to receive the spring 12, thus forming a seat for one end 95 thereof upon the edge face of shank 2 and to prevent any possibility of the spring becoming detached from between the carriage and the said yoke. In the inner edge of the extension 11^a, is provided a transverse slot 100 or notch 11^c, in which the projecting lug 10^a, of the movable yoke is fitted, retaining it in position on the carriage 11.

The pipe attachment embodied in my invention as shown in Figs. 4 and 5 consists 105 of a cross-sectionally flat jaw 13, bifurcated at its rear end to straddle the shank 2, whereby the arms 13^a, formed by the bifur-

cations are arranged in planes at either side of the shank and there securely clamped adjacent to the inner edge of the jaw 1, by means of a thumb bolt 14; the width of this 5 jaw is equal to that of the fixed jaw of the wrench and its operative face is toothed or serrated; the sliding jaw 3 being adjusted to suit the size of the pipe to be operated upon enables the convenient gripping and 10 turning of the same.

When it is desired to use the wrench the primary adjustment of the sliding jaw may be obtained by the operator pressing on the finger lug 10^a, of the movable yoke 10, to 15 move the latter out of engagement with the teeth 8, the operator can now move the jaw 3 in either direction on the shank 2. After this adjustment, if it be found that the nut is not suitably gripped, the secondary adjustment may be resorted to, which is obtained 20 by turning the knurled disk 7, thereby moving the sliding jaw away from the carriage.

From the foregoing it is apparent that I produce a simple inexpensive device which 25 will be strong and durable, but in attaining these ends I do not wish to be limited to the precise details herein set forth, inasmuch as minor changes in the form, proportion, and

exact manner of assemblage of the parts may be made without departing from the 30 spirit of the invention.

Having thus described my invention, what I claim is—

A wrench of the type described comprising a shank having a fixed jaw and provided with transversely disposed ratchet teeth, a movable jaw slidable on the shank, a carriage slidably receiving said shank and provided with a transverse slot in the extended end thereof, a yoke embracing the 35 carriage having a lug adapted to locking engagement with the slot in the same, a toothed locking portion in the opposite end of the yoke for engaging the teeth in the shank, means for adjustably connecting the 40 movable jaw and carriage together, and an expansion spring interposed between the yoke and the shank for sustaining the yoke in engagement therewith.

In testimony whereof I affix my signature 45 in presence of two witnesses.

ARTHUR G. HUNTER.
